ROTARY ENGINE

Sebastiano Strazzulla, Genova, Italy

Application November 1, 1935, Serial No. 47,869
In Italy December 20, 1934

4 Claims. (Cl. 253—68)

This invention relates to a rotary engine by which it is possible to employ as driving fluid combustion gases, superheated or usual steams.

The object of the invention is to provide an engine of the above kind by which the drop of pressure and/or temperature of the fluid measured at the inlet and at the outlet side is transformed for the maximum part to useful mechanical power.

According to the invention this is attained by providing a rotor having substantially the form of two frustums of cones joined by their larger bases and by arranging on this rotor a number of helical grooves running from the outer ends of the rotor to its central part and by arranging in these grooves a number of partition vanes that are perforated in their top part and solid in their bottom part. The perforations of the partitions are made in such a direction as to blow the driving fluid against one of the side-walls of the corresponding groove and against the solid part of the next following partition.

The sectional area of the grooves increases from the inlet to the outlet end thereof and the partitions are arranged in each groove at an increased distance from the inlet to the outlet end. In this manner the total drop of pressure and temperature is subdivided into a number of partial expansions by each of which the gas works principally by impact against the solid walls.

An embodiment of the invention is shown by way of example in the attached drawings in which:

Figure 1 is a side view of the rotor of an engine according to the invention;

Figure 2 is a side view of the complete engine;

Figure 3 is a section on line III—III of Figure 2;

Figure 4 is a plan view at a larger scale of a portion of two adjacent grooves;

Figure 5 is a vertical section through one of the grooves;

Figures 6 and 7 are respectively a front view and a transversal section of fluid inlet member, 45 and

Figure 8 is a section on line VIII—VIII of Figure 2.

According to the invention the rotor A is constituted by a hollow body shaped as two frustums of cones joined by their larger bases. The outer surface of the frustums of cones is subdivided by a number of helical walls W into a number of grooves B and B' the sectional area of which increases from the outer end towards the center portion of the rotor, where they end into outlet chambers D of substantially prismatical shape.

The bottoms of the grooves are constituted preferably by a number of substantially cylindrical sections joined together by upright walls, 60 as shown in Figure 5.

The rotor A is housed with a tight fit in a casing H showing a like form. Both on the rotor and on the shaft E keyed to the rotor, as well as on the casing or stator H suitable labyrinth joints C—C'—C''—C''' are arranged in order to prevent the leakage of the driving fluid between the shaft E and the casing.

At the outer ends of the stator two annular fluid distributors J—J' are inserted. These distributors blow the fluid into the inlet ends of the grooves (Figures 6 and 7). At the center of the stator an annular collector L is arranged from which two diametrically opposite outlet conduits M are fitted. The fluid is fed to the annular distributors J and J' through pipes N and N' leading from a valved distributing pipe N''. These distributors are in the nature of nozzles for feeding the fluid to the opposite ends of the rotor A.

The working of the engine is as follows:

The fluid admitted through the pipes N and N' into the annular distributor J—J' is blown through openings O against one of the solid side walls of the corresponding helical groove and against the solid part of the first partition P' (Figure 5) and thus imparts to the rotor a certain impulse. The fluid expands into the chamber defined by the groove, the corresponding portion of the annular distributor the corresponding portion of the casing and the first partition P' and flows then through the openings of the first partition P' and is blown in the same manner against the second partition P' and so on to the outlet end. Owing to the fact that the fluid impacts against the solid part of the partitions P it drives the rotor and the shaft keyed thereto with a great efficiency. As the total expansion of the fluid is effected in a number of partial expansions and on a great length, the drop of pressure and temperature is correspondingly subdivided thus permitting to employ high pressure and high temperature gases or steam without need for artificial cooling.

It is understood that the invention may be embodied in many other ways within the spirit of the annexed claims.

I claim:

1. A rotary engine comprising in combination a hollow stator of substantially biconical shape, means for supporting this stator, a substantially biconical rotor snugly fitting within the said stator, a shaft integral of this rotor, journal bearings on the supports of the stator, labyrinth joints at the ends of the stator and complementary labyrinth joints on the adjacent part of the rotor and the shaft, a double set of helical grooves leading from the ends of the rotor to the center portion thereof, a number of partially perforated partitions fitted at increasing distances within the said grooves, solid annular distributors ar-

ranged in the stator adjacent the inlet ends of the helical grooves of the rotor, nozzles on these distributors, a fluid supply pipe connected to either of these distributors, and fluid discharge conduits arranged in diametrically opposite points of the center portion of the stator, in front of the discharge ends of the helical grooves.

2. A rotary engine according to claim 1, by which the helical grooves are of increased sectional area from their inlet to their outlet ends, outlet chambers being provided at the outlet ends of said grooves.

3. A rotary engine according to claim 1, by which the partitions fitted within the helical grooves have nozzle like perforations in their upper part through which the driving fluid is

projected against one of the said walls of the corresponding groove and against the lower solid portion of the next following partition.

4. A rotary engine according to claim 1, by which the helical grooves have their bottom part 5 constituted by a number of cylindrical sections of an increased length and width from inlet towards the outlet end of the grooves, the said cylindrical sections being connected with each other by means of solid upright walls against which 10 the partitions are fitted, constituted of blade like members solid in their lower part and having nozzle like perforations in their upper part, with their axes directed against the solid part of the next lying partition.

SEBASTIANO STRAZZULLA.
